Primary Examiner—Brian N Vinson

(74) Attorney, Agent, or Firm:—Richard B. Klar

(73) Assignee: **Jakks Pacific, Inc.**, Malibu, CA (US)

(57) CLAIM

(**) Term: **14 Years**

The ornamental design for a tongue-shaped tape dispenser for dissolvable film strips, as shown and described.

(21) Appl. No.: **29/185,354**

DESCRIPTION

(22) Filed: **Jun. 25, 2003**

FIG. 1 is a top plan view of a tongue-shaped tape dispenser for dissolvable film showing my new design;

(51) LOC (8) Cl. **20-02**

FIG. 2 is a bottom plan view thereof;

(52) U.S. Cl. **D6/518**

FIG. 3 is a left side elevational view thereof;

(58) Field of Search **D6/515-518; D3/201;**

FIG. 4 is a front end elevational view thereof;

D9/65-99; 206/215, 557, 37-38; 211/13.1;

FIG. 5 is a rear end elevational view thereof;

221/33-36, 47-52, 56-63; 222/181, 281-282

FIG. 6 is a top plan view thereof, in an open position;
